UNITED STATES PATENT OFFICE.

MORTIMER DU PEROW, OF WASHINGTON, DISTRICT OF COLUMBIA.

RADIORECEIVER.

Application filed March 24, 1926. Serial No. 97,126.

This invention relates to a radio receiver adapted to take the place of the ordinary ear phones and to emit sound waves in loud enough tones so that they may be heard at a distance from the receiver. In carrying out the invention, I provide a hollow body having a plurality of openings which are closed by diaphragms. Two of these diaphragms are arranged opposite one another, and magnets, connected in series or in multiple in the receiving circuit, are arranged adjacent these latter diaphragms and adapted to vibrate them simultaneously in opposite directions, whereby the air within the chamber is alternately compressed and rarefied. A partition is preferably placed between these two diaphragms so that the air set in motion by the one will not impinge directly upon the other, and the force of the vibrations will be directed outwardly toward the periphery of the casing where several other sensitive diaphragms are arranged.

In the accompanying drawing,

Fig. 1 is a diagrammatic view showing a direct-coupled receiving set with my improved sound reproducing device connected therein;

Fig. 2 is a section through the receiving device, taken on the line 2—2 of Fig. 3; and,

Fig. 3 is a similar view taken on the line 3—3 of Fig. 2.

Referring to the drawing, *a* represents diagrammatically the circuits of a receiving set, which need not be particularly described, *b* represents a detector or rectifier, and *c* indicates the receiver of my invention, connected in series with the rectifier in the place of the usual head phones. It is to be understood that the receiver may be used in the simple set shown or may be substituted for the head phones or loud speakers in the various forms of radio receiving sets having current amplifying means.

The receiver comprises a hollow body 1, preferably made of molded insulating material, and of cylindrical form. This drum-shaped body has openings in its ends which are closed by diaphragms 2 and 3, of magnetizable metal, and it also has a plurality of openings in its periphery which are closed by diaphragms 4, 5, 6, and 7, these latter diaphragms being preferably considerably larger than the diaphragms 2 and 3.

A partition 8 is arranged midway between the metal diaphragms and parallel therewith,

this partition being in the form of a disk which extends into close proximity to the peripheral diaphragms. The purpose of this partition is to prevent the air, which is set in motion by the vibration of one of the smaller diaphragms, from directly affecting the opposing diaphragm, and to cause the impulses to be directed outwardly toward the peripheral diaphragms.

Magnets 9 and 10 are arranged with their pole-pieces close to the diaphragms 2 and 3, respectively, and the coils of these magnets are connected in series in the receiving circuit, as shown in Fig. 1, but they may be connected in multiple. The magnets cause the diaphragm to be pulled outward simultaneously and to be released simultaneously, so that the air vibrations within the casing will have twice the mechanical force that they would have if only one diaphragm were used. The force of the vibrations is transmitted to the diaphragms on the periphery of the casing, with the result that the latter emit sounds which can be heard at a distance from the device.

The magnets are mounted on the inner sides of plates 11 which extend over the ends of the drum, and these plates enclose the diaphragms 2 and 3 so that the latter will not be affected by air vibrations from sources external to the drum and so that sound waves set up by these diaphragms will not pass out and interfere with sound waves emitted by the peripheral diaphragms.

What I claim is:

1. A radio receiver comprising a hollow body having a plurality of openings and diaphragms closing said openings, said body and diaphragms forming an enclosed air chamber, one of said diaphragms being of magnetizable metal, and a magnet, supported independently of the diaphragms, having a polepiece arranged close to the latter diaphragms.

2. A radio receiver comprising a hollow body having more than two openings and diaphragms closing said openings, said body and diaphragms forming an enclosed air chamber, two of said diaphragms being of magnetizable metal, and magnets, supported independently of the diaphragms, connected to a common current source and adapted, when energized, to act oppositely on the latter diaphragms.

3. A radio receiver comprising a hollow

body having more than two openings and diaphragms closing said openings, said body and diaphragms forming an enclosed air chamber, two of said diaphragms being of 5 magnetizable metal and being arranged opposite one another, and magnets, supported independently of the diaphragms, connected to a common current source and adapted when energized to act oppositely on the latter diaphragms.

4. A radio receiver comprising a hollow body having a plurality of openings and diaphragms closing said openings, said body and diaphragms forming an enclosed air chamber, two of said diaphragms being of magnetizable metal and arranged opposite one another and the other diaphragms being arranged in planes at right angles to the planes 15 of said magnetizable diaphragms, a parti-

tion arranged between said latter diaphragms 20 and extending close to said other diaphragms, and magnets having pole pieces adjacent said magnetizable diaphragms and connected to a common current source.

5. A radio receiver comprising a hollow 25 cylindrical body having openings in its sides and a plurality of openings in its periphery and having diaphragms closing said openings, the diaphragms in the sides of the casting being of magnetizable metal, a partition 30 between said latter diaphragms and extending close to the diaphragms in the periphery, and magnets having pole pieces adjacent said magnetizable diaphragms and connected to a common current source. 35

In testimony whereof I hereunto affix my signature.

MORTIMER DU PEROW.
